RICHARD DUANE GREEN, OF TRENTON, NEW JERSEY, ASSIGNOR TO JOHN A. ROEBLING'S SONS COMPANY, OF TRENTON, NEW JERSEY, A CORPORATION OF NEW JERSEY

WIRE ROPE AND METHOD OF MAKING THE SAME

Application filed October 3, 1931. Serial No. 566,648.

This invention relates to wire rope and to methods for making the same; the especial object of this invention being to provide an improved wire rope adapted for general operating service and securing safety in use by disclosing promptly any breakage of wires.

Operating service conditions to which wire rope may be subjected vary greatly. For example, a rope sometimes must operate at slow speed, under extremely high tension and bending over sheaves and drums of large diameter. Or the speed may be extremely high, the tension may be moderate or low and the sheaves or drums may have small or medium diameters and these conditions are capable of many combinations. It would be impracticable to provide separate ropes for each possible operating condition, and it is important that the rope itself when placed in service should readjust its manufactured condition to fit its operating conditions.

In the manufacture of the ordinary standard wire rope, a plurality of substantially straight wires are laid up helically on a central core to form a strand and a plurality of such straight strands are laid up helically on a core to form the finished rope. The rope so formed is capable of accommodating itself readily to various operating or service conditions. This can readily be seen when it is considered that in such standard ropes the wires in the strands and the strands in the ropes are not formed to definite permanent helices so that the wires and strands readjust themselves, that is, assume proper relative positions for equalizing stresses and strains.

Rope manufactured according to this standard method has the disadvantage that inequalities in the wire tensions or strand tensions when closed into rope, or inequalities in size and hardness of the center, though not occurring together at any given section, tend to concentrate at one point during the course of readjustment. Such inequalities have been found to travel a considerable length of rope and concentrate at the same point, with the result that rapid deterioration with con-

sequent short rope life takes place, which would not occur if such concentration of these inequalities were prevented.

A second method of manufacture has been employed, that of the helically formed wire and strand. With this method, the individual wires are formed into permanent helices of the form desired and laid about the core to form straight strands, after which the straight strands themselves are formed into permanent helices and laid about a core to form the finished rope. The wires and strands may be formed to helices of substantially the form they possess in the completed strand or rope, but preferably are formed to a helix having a slightly smaller diameter than the diameter of the cores, so that the wires in the strands and the strands in the rope have a tendency to hug the cores. The strands only may be formed into permanent helices before or in laying them up, the strands being of standard construction, and in multiple layer rope only the strands at the outer layer or layers may be thus formed into permanent helices before or in laying them up.

With constructions under the second method, travel of inequalities from one section to another is prevented, but readjustment to operating conditions is interfered with, so that such a rope does not secure maximum service under various operating conditions. Moreover, a defect which exists in such strand or rope, especially in rope in which the strands consist of wires thus formed to permanent helices, is that a broken wire or strand does not spring out from the core, and this means of immediate detection of broken wires or strands is lost, with consequent danger of the continued use of a rope too weak for the load, which may result in serious accident, as for instance, in elevator service.

This defect as to safety exists, also, in wire strand or rope made under previous methods combining the two methods above described, that is, forming some of the wires or strands throughout into permanent helices before or in laying them up, and combining such wires or strands with wires or strands not formed

into permanent helices; or by dividing the rope into longitudinal sections, some sections being made by forming all the wires or strands throughout such sections into permanent helices before or in laying them up, and other sections being made by the standard construction of not forming any of the wires or strands into helices before laying, as in my prior Patent No. 1,777,117, September 30, 1930.

10 In accordance with the present invention, the strand or rope is formed in sections, some or all of which have wires or strands formed into permanent helices before or in laying them up, but each of such sections having formed wires or strands has also unformed or standard construction wires or strands, and these wires or strands of standard construction act as a tell-tale for indicating the rope's condition and enabling the detection of broken wires or strands and aid in securing the adjustment to different operating conditions.

15 In making strand, each of the wires, and in making rope, each of the strands is made in alternating sections of formed and unformed wires or strands, so that each wire or strand is partially of standard construction permitting adjustment for operating 20 conditions and showing breakage by the springing out of a broken wire or strand, and partially of wires or strands formed into permanent helices before or in laying so as to avoid travel of irregularities through 25 such wires or strands. In laying up the strand or rope, such sections of previously formed wires or strands will not be laid in the same longitudinal sections of the strand or rope and thus all sections of the 30 final strand or rope having formed wires or strands will have some of standard construction.

35 It usually will be found preferable in use and manufacture that the sections of strand or rope above described shall alternate throughout the strand or rope without any sections of standard construction, but in some cases it may be desirable to provide sections wholly of standard construction, that is, having no wires or strands formed with permanent helices before or in laying them up. This will depend upon the operating 40 conditions under which the strand or rope is to be used.

45 This new construction, in either form above described, will secure a better result than that of my prior Patent No. 1,777,117 in respect to adjusting itself to operating 50 conditions and avoiding the disadvantage of the travel and concentration of inequalities, and has the further important feature that every part of the length of the strand or rope has unformed wires or strands present to indicate the rope's condition, instead of 55 having some sections consisting only of wires

or strands formed into permanent helices before or in laying them up, which sections would be without wires or strands giving definite indication of the rope's deterioration by the springing out of wires or strands.

60 The length of the different sections may be varied as desired, in accordance with the operating conditions under which the strand or rope is to be used, and in strand or rope containing sections of wholly standard construction the sections containing wires or strands formed to permanent helices may be quite short relatively to the standard sections for rope of some types and for some purposes, and the reverse for other types or other purposes. In forming wire rope under the invention, also, the rope may be formed of strands laid up in accordance with the present invention, but the strands themselves being of the usual standard construction, my invention being of special importance in connection with the strands forming the rope.

65 The drawing illustrates preferred forms of embodiment of the invention and these constructions and the method of making them will now be described in detail and the features forming the invention then specifically pointed out in the claims.

In the drawing:

70 Figure 1 is an outside view of a single layer wire rope, consisting of six strands with core;

75 Figure 2 is a cross section of the same on an enlarged scale, showing the strands as formed of nine wires with core;

80 Figure 3 is a view similar to Figure 1, showing the preferred construction of the strand in the rope of Figures 1 and 2; and

85 Figures 4 and 5 are views similar to Figures 1 and 3, showing a modified form with sections wholly of standard construction.

90 Referring now particularly to Figures 1 to 3, the rope shown is made up of a plurality of standards 1-6 surrounding a central core α and each of these strands is composed of a plurality of individual wires 7-15 laid up on a central core γ . The rope and strands are shown as made up of a number of alternate sections A' , A^2 , which are made by forming some of the strands into permanent helices before or in laying them up on core α with strands of standard construction in each section.

95 As shown, section A' is made of strands 1, 3, 5, formed to permanent helices, and the alternate strands 2, 4, 6 unformed, and in section A^2 , the construction of these strands is reversed, strands 1, 3, 5 being unformed and strands 2, 4, 6 formed, but it will be understood that this arrangement as to the number and position of the formed and unformed strands may be varied. The sections A' and A^2 may be alternated through the rope length and may be of various lengths relatively to

each other, depending upon the type of rope desired. The strands, also, preferably are formed by the same construction, and this is illustrated in Figure 3 in connection with strand 1 of the rope. As shown, strand 1 has sections 1^a with wires 7, 9, 11, 13, 15 formed and the others unformed and this arrangement is reversed in section 1^b, wires 7, 9, 11, 13, 15, being unformed and wires 8, 10, 12, 14 formed. The length of the sections of the strands and the alternating arrangement of formed and unformed wires therein is shown as the same as that of the strands in the rope, but neither of these features is 15 essential.

In Figures 4 and 5, I have shown constructions similar to those of Figures 1 to 3, except that between the sections A', A² of the rope are sections A³ wholly of standard construction, and between the sections 1^a and 1^b of the strands are sections 1^c of standard construction. The length of these sections of standard construction and of the other sections will be varied as desired, in accordance 20 with the characteristics and use of the rope.

With the rope so constructed, it has been found that the readjustment of the wires in the strands and of the strands in the rope to compensate for various operating conditions 25 is fully secured, while the sections in which some of the wires and strands have been formed into permanent helices before or in laying prevent the traveling of inequalities, and that a rope constructed in accordance 30 with this invention is well suited for all operating conditions. A rope constructed in accordance with the foregoing method is especially desirable for elevator cables or similar uses where it is important that a break in the 40 wires or strands be apparent upon inspection of the cable.

The invention has been illustrated as applied in connection with a single layer rope, but it will be understood that it is equally 45 applicable to multiple layer strands or ropes. In such strands or ropes, it is most important, of course, that the outer layer should have the standard wires or strands throughout the sections for tell-tales and such multiple layer 50 strand or rope may be made with only the outer layer of such construction. It is preferable, however, to use the same construction on the inner layer or layers, also, so as to get a uniform action of the different layers 55 and aid in accommodating different operating conditions and preventing travel of irregularities.

It will be understood that the invention is not limited to the particular constructions or 60 arrangements of wires or strands shown and described, but that many modifications may be made within the invention defined by the claims.

What I claim is:

65 1. The method of making stranded wire

structure of the class referred to which comprises forming the components into permanent helices throughout portions of their length and laying them to form the wire structure in sections longitudinally of the 70 structure with some of the components thus formed and some unformed in the same section.

2. The method of making stranded wire structure of the class referred to which comprises forming the components into permanent helices throughout portions of their length and laying them to form the structure in alternate sections longitudinally of the 75 structure, with some of the components thus formed and some unformed in each section.

3. The method of making stranded wire structure of the class referred to which comprises forming some of the wire components into permanent helices throughout portions 80 of their length and laying them with components not formed into permanent helices to form the stranded wire structure in sections longitudinally of the structure with some of the sections having some of the components thus formed and some unformed and other sections having none of the components thus 85 formed.

4. The method of making wire rope which comprises forming strands into permanent 90 helices throughout portions of their length and laying them to form the rope in sections longitudinally of the rope with some of the strands thus formed and some unformed in the same section.

5. The method of making wire strand which comprises forming wires into permanent 95 helices throughout portions of their length and laying them to form the strands in sections longitudinally of the strand with some of the wires thus formed and some unformed in the same section.

6. The method of making wire rope which comprises forming the wires into permanent 100 helices throughout portions of their length and laying them to form strand sections longitudinally of the strand with some wires thus formed and some unformed in the same section, forming the strands into permanent helices throughout portions of their length and laying them to form the rope in sections longitudinally of the rope with some strands thus formed and some unformed in the same section.

7. The method of making wire rope which comprises forming some of the wires into permanent helices throughout portions of their length and laying them into strands with wires not so formed to form the strands in sections longitudinally of the strand with some of the wires thus formed and some unformed in some sections and no wires thus formed in other sections, and forming some of the strands into permanent helices throughout 115 portions of their length and laying them 120

into rope with strands not formed into permanent helices to form the rope in sections longitudinally of the rope, with some of the strands thus formed and some unformed in some sections and no strands thus formed in other sections.

8. A continuous stranded wire structure of the class referred to formed in sections longitudinally of the structure and having some of its wire components formed into permanent helices throughout only portions of their length, some of the sections containing wire components formed into permanent helices within said sections and other components not so formed within said sections.

9. A continuous stranded wire structure of the class referred to, formed of alternating sections longitudinally of the structure and having some of its wire components formed into permanent helices throughout only portions of their length, each of said sections comprising some components formed into permanent helices within said sections and other components not so formed within said sections.

10. A continuous stranded wire structure of the class referred to, formed of alternating sections longitudinally of the structure, each of said components being formed into permanent helices throughout portions of its length and said components being so laid together that each of said structure sections comprises some components formed into permanent helices and other components not so formed.

11. A continuous stranded wire structure of the class referred to, formed in sections longitudinally of the structure, some of said sections consisting of components not formed into permanent helices, and other sections comprising some components formed into permanent helices and other components not so formed.

12. A continuous stranded wire structure of the class referred to, formed in sections longitudinally of the structure, some of the components being formed into permanent helices throughout portions of their length and said components being so laid together with components not so formed that some of said sections consist of components not formed into permanent helices, and other sections comprise some components formed into permanent helices and other components not so formed.

13. A continuous wire rope formed in sections longitudinally of the rope and having some of its strands formed into permanent helices throughout only portions of their length, some of said sections comprising some strands formed into permanent helices within said sections and other strands not so formed within said sections.

14. A continuous wire rope formed in sections longitudinally of the rope, some of said

sections comprising some strands formed into permanent helices and other strands not so formed, all the strands of the rope having portions of their length formed into permanent helices and other portions not so formed. 70

15. A continuous wire rope formed in sections longitudinally of the rope, some of said sections consisting of strands not formed into permanent helices and other sections comprising some strands formed into permanent helices and other strands not so formed. 75

16. A continuous wire rope formed in sections longitudinally of the rope, some of said sections comprising some strands formed into permanent helices and other strands not so formed, each of said strands being formed in sections longitudinally of the strand, some of said strand sections comprising some wires formed into permanent helices and some wires not so formed. 80

17. A continuous wire rope formed in sections longitudinally of the rope, some of said sections comprising some strands formed into permanent helices and other strands not so formed, each of said strands being formed in sections longitudinally of the strand, some of said strand sections comprising some wires formed into permanent helices and some wires not so formed, the strands of the rope and the wires of the strands having portions of their length formed into permanent helices and other portions not so formed. 90

In testimony whereof, I have hereunto set my hand.
